3 Claims. (Cl. 170—163)

1

This invention relates primarily to propellers and more particularly to hydraulically actuated propeller blade pitch changing mechanisms.

Heretofore, most pitch changing mechanisms of the above description have been so constructed that the hydraulic unit is necessarily located on the opposite side of the propeller from the engine that drives it. This is objectionable because no satisfactory method has yet been devised for effectively venting and draining hydraulic units thus located. Such constructions are also undesirable because of the resulting weight concentration at a point so remote from the propeller shaft bearings, which are generally mounted in the engine housing. As a consequence, unwarrentably high vibratory and bending stresses are frequently attributable to arrangements of this type. In order to overcome these objections, designs have been proposed where the hydraulic mechanism is located between the propeller and engine, but while that location is desirable, the designs in question include faults that render them unsatisfactory in practice, as is apparent from what follows.

There are two classes of the last-mentioned designs. In one class, the use of a rotary hydraulic motor with impeller vanes constitutes the principal feature, and it is well known that the cost of manufacturing and maintaining such mechanisms is extremely high. In addition, they are heavy, bulky and subject to excessive leakage. In the other class, the hydraulic unit consists essentially of a stationary cylinder and non-rotating piston. This construction is obviously objectionable because of the fact that the total force exerted by the piston must be transmitted to the blade turning mechanism, located on the propeller hub, through the medium of a thrust bearing running at the same high speed as the propeller. To those familiar with the art, a bearing which would meet such severe operating conditions is too heavy and difficult to lubricate and also requires too much space to be adaptable to practical use for the purpose concerned.

Accordingly, it is one of the objects of the present invention to provide a hydraulically actuated pitch changing mechanism for propellers, which does not include any of the objectionable features enumerated in the preceding paragraphs, and which is so compact that it can readily be in-

2

stalled in small space between any propeller and the engine that drives it.

Another object of the present invention is to provide an improved and novel hydraulically actuated pitch changing mechanism for variable pitch propellers which is of extreme simplicity, positive and dependable in operation, light in weight, and which may be easily and cheaply manufactured, assembled and maintained.

10 Another object of the present invention is to provide a propeller of the above type wherein no springs or counterweights are employed in any part of the mechanism, and in which all hydraulic connections thereto are outside of the engine casing.

15 Another object of the invention is to provide a hydraulically actuated propeller blade pitch changing mechanism comprising an annular cylinder and longitudinally movable piston therein, 20 concentrically mounted with the propeller shaft and rotatable therewith.

25 Another object of the invention is to provide a propeller of the above description wherein the cylinder and piston are located between the engine and propeller, so as to concentrate the weight thereof close to the bearings that support the propeller shaft and so as to permit of the use of improved means for supplying hydraulic fluid to the cylinder.

30 Another object of the invention is to provide a hydraulically actuated pitch changing mechanism for variable pitch propellers, which does not require any drilling or cutting of any part of the propeller shaft, and in which no fluid is carried 35 in the interior thereof. Such a design is advantageous in that it does not weaken the propeller shaft and leaves the usually hollow central portion thereof entirely free for gun-fire, etc.

40 Another object of the invention is to provide an improved and simplified hydraulic device for transferring fluid under pressure from one member to another moving relatively thereto, and particularly from the engine oil pump or other source 45 of fluid supply to a rotating hydraulic propeller pitch changing mechanism.

In connection with the above, it is a further object of the invention to provide a fluid transfer arrangement comprising a ring mounted concentrically with a rotatable shaft wherein no fluid

seal between the ring and the shaft is required, and in which the fluid seal surfaces are flat.

A further object of the invention in connection with the above is to provide a fluid transfer arrangement which is readily accessible and which may be easily adjusted to compensate for wear, if necessary.

A further object of the invention in connection with the above is to provide an improved device for conveying fluid between relatively moving members wherein said members are hydrostatically balanced with respect to one-another.

A still further object of the invention is to provide a system for lubricating the propeller blade thrust bearings, and other moving parts mounted on or in the propeller hub wherein the lubricant is completely isolated and independent of the fluid in the hydraulic system employed to vary the pitch of the propeller blades.

Another object of the invention is to provide means for venting and draining the hydraulic pitch changing cylinder by centrifugal action in such a manner that any fluid, such as oil, leaking into the vented part of the cylinder is returned to the engine oil sump or other source of supply utilized in the hydraulic system.

Another object of the invention is to provide means for continuously equalizing during rotation of the propeller hub the amount of lubricant carried in all blade sockets, regardless of inequalities in the original distribution thereof and regardless of leakage thereof from any one or more of the sockets.

These and other objects and advantages of the invention will be made more apparent hereinafter by the following detailed description when taken in conjunction with the accompanying drawings, which illustrate one embodiment of the invention.

In the drawings,

Fig. 1 is a sectional view of a propeller blade pitch changing mechanism constructed in accordance with the principles of the present invention, with the section above the longitudinal center line taken in a plane parallel to and through the axis of the propeller shaft and the axis of one of the blade sockets; the lower half of the section being in a plane parallel to and partially through the propeller shaft axis but perpendicular to the axis of another blade socket spaced 120° from the one above;

Fig. 2 is a front end view partly in section of the propeller hub of Fig. 1;

Fig. 3 is a horizontal sectional view taken substantially on line 3—3 of Fig. 2;

Fig. 4 is an enlarged detail view of a part of the oil leakage collecting and draining elements;

Fig. 5 is a vertical sectional view taken substantially on line 5—5 of Fig. 1;

Fig. 6 is a vertical sectional view taken substantially on line 6—6 of Fig. 1; and

Fig. 7 is an enlarged detail view partly in section taken on line 7—7 of Fig. 1.

Referring first to Figs. 1 and 2, a propeller hub, indicated generally by reference numeral 11, is shown mounted on a propeller shaft 12, which is supported and driven by an engine having a nose housing indicated by the reference numeral 10. The propeller shaft 12 is adapted to drive the propeller hub 11 through the usual means, such as interengaging splines 13. In the illustrated embodiment of the present invention, as most clearly shown in Fig. 2, the propeller hub 11 has three blade sockets, each indicated generally by reference numerals 14. It is to be understood,

however, that no limitation is imposed in this connection, for obviously either a greater or smaller number of blades could be used without affecting any of the principles involved. The blade sockets 14 support associated propeller blades, only the shanks 16 of which are shown, in such a manner, as hereinafter described in detail, that the pitch thereof may be altered.

Secured to the front of the propeller hub or the left hand end, as shown in Fig. 1, by screws such as 15 is a cap 16 which serves to keep foreign material, such as dust and dirt, out of the propeller shaft and hub mounting units. The propeller hub 11 has on its right hand end, as shown in Fig. 1, a radially extending circular flange 17 formed integrally with the blade sockets 14, and secured to the right hand or engine side of this flange, by bolts such as 18, is a cylinder 18, concentrically mounted with the propeller shaft 12. Secured to the right hand end of the cylinder 18 by the bolts 18 and cap screws, such as 19—a, Fig. 6, is a circular head or cover member 21, Fig. 1, having a central bore adapted to fit slidably on the propeller shaft 12. The cylinder 18 together with the propeller shaft 12 and head 21 form an annular hydraulic pressure chamber which is closed at the propeller end by the hub 11 and flange 17. Inasmuch as the cylinder 18 and the head 21 are secured to the propeller hub 11, they rotate therewith and with the propeller shaft 12. In the central bore of the head 21 is a groove 22 in which a packing ring 22—a of suitable material may be provided to prevent the escape of oil from the hydraulic chamber along the shaft 12.

Located in the above described hydraulic chamber is an annular piston 23 which is adapted to move longitudinally therein so as to effect pitch changes of the propeller blades in a manner hereinafter explained. The piston 23 has secured to the right hand face thereof by cap screws, such as 24, and a metal disc, such as 25, a double flanged packing ring 25 of suitable material, such as leather, which engages both the inner wall of the cylinder 18 and the outer surface of the propeller shaft 12 to prevent the escape of hydraulic fluid past the piston 23. The outer flange of the packing ring 25 is held against the cylinder 18 by centrifugal force and its inner flange is pressed against the propeller shaft by a circular spring 26—a. Secured to the piston 23 are three rack rods 27, one for each propeller blade, which are cylindrical in cross-section throughout the end portions thereof. Each of the rods 27 is slidably mounted in a bore 28, parallel with the propeller shaft, formed in the body of the hub 11. The outer or left end of each bore 28, as viewed in Fig. 1, is closed by a plug 29, and the space at the end of the bore 28, between the rod 27 and the plug 29, is vented by a groove 29—a formed in the rod 27. The rods 27 are secured to the piston 23 by nuts, such as 30, in threaded engagement therewith and are prevented from rotating in their mounting holes in the piston by keys, such as 31, Fig. 3. The rack rods 27 serve to support and guide the piston 23 in its back and forth movement in the cylinder 18, and, in the preferred embodiment, a slight amount of clearance is provided between the piston and cylinder and between the central bore in the piston and the shaft 12, so that only the hydraulic packing ring 25 bears on the cylinder wall and on the shaft. Packing rings such as 32 in the flange portion 17 of the hub surround the rack rods 27 to prevent leak-

age to and from the hydraulic chamber and the blade sockets.

In the central portion of each rack rod 27, Fig. 1, 2 and 3, a rack of gear teeth 33 is formed, and these teeth are adapted to engage cooperating teeth 35 of a spur gear segment 34—a formed on a split sleeve member 34, which is split along the longitudinal axis thereof and is clamped to an associated blade shank 36 by a clamping ring 37 of conventional design. All of the spur gear segments 34—a secured to the several blade shanks 36 have the same pitch diameter. The blade shank 36 is shown in full in Fig. 1 and has radial flanges or shoulders, such as 38 and 39, engaging mating flanges 41 and 42, respectively, on the inside of the split sleeve 34. In this manner, sleeve 34, which is rotatably retained in the blade socket, in turn retains the blade shank and integrally formed blade against the action of centrifugal force. The sleeve 34 is prevented from rotating relatively to the blade shank by the clamping ring 37.

The blade sleeve 34 has a radial shoulder or flange 43 which engages the inner race 44 of the lowermost of a stack of ball thrust bearings 46. The outer races 47 of the bearings 46 engage the inside of the blade socket 14 and are held therein by a nut 48 in threaded engagement therewith. A locking key 49 is provided to prevent rotation of the nut 48 relatively to the blade socket after being tightened, and the key is held in place by screws, such as 51. More than one key 49 may be employed, such keys being placed in radial slots in the upper surfaces of the blade socket 14 and the locking nut 48. A packing ring 52 surrounds the blade sleeve 34 at the nut 48 to prevent leakage of lubricant from the blade socket.

The inner end of the blade shank 36 is recessed and has therein a thrust member 53 faced with a non-metallic disc 54 which bears on a mating surface such as 56 formed on the longitudinal portion of the hub 11. The radial force developed by the tightening of the locking nut 48 is transmitted through the thrust bearing 46, sleeve 34, blade shank 36, thrust member 53 and disc 54 to the surface 56 of the propeller hub, and thus serves as means whereby the thrust bearing 46 may be preloaded.

The head 21 of the hydraulic cylinder 18 has, as shown in Fig. 1, an extension or sleeve portion 57 surrounding the propeller shaft 12. The extreme end of the sleeve portion 57 is threaded to engage a nut 58, and has a smooth cylindrical surface to the left of said threaded end upon which is located an oil, or other fluid, transfer ring 59. The oil transfer ring 59 fits slidably upon the sleeve portion 57 of the head 21, and the two radial faces thereof are ground flat. The head 21 has a radial surface 61, that is ground flat, against which the left hand face of the oil transfer ring abuts. The inside face 58—a of the nut 58, against which the right hand face of the transfer ring abuts, is also ground flat.

The oil transfer ring 59 has a relatively deep circular groove 62 in its left hand face and a relatively shallow circular groove 67 in its opposite face. It is preferable, for reasons that will later be made apparent, that these two grooves 62 and 67 be concentric and have the same inside and outside diameters, though obviously such a construction is not essential to satisfactory operation of the oil transfer ring. A hole 63 is drilled straight through the ring 59 to connect the grooves 62 and 67 with each other. A radial hole 75

64—a is drilled from the outside periphery of the ring 59 to meet the hole 63, and is tapped or otherwise adapted to take a fitting 64 to which may be connected a tube 66, preferably of the armored flexible type, leading to an oil pump or other source of fluid pressure supply, by way of suitable manual or automatic control valves, or any desirable combination of such valves.

One or more holes or passageways such as 68 10 are drilled through the head 21 opposite the groove 62 in the oil transfer ring 59 whereby an oil connection is established from the transfer ring 59 to that section of the hydraulic chamber to the right of the piston 23. Accordingly, oil entering the ring 59 under pressure from the tube 66 may pass to the cylinder to force the piston to the left.

In order to prevent the oil transfer ring 59 from rotating with the propeller shaft and hub assembly, a pin 69 is forced radially into a suitable hole in the transfer ring and has its opposite end retained in a longitudinal slot 69—a in the interior of a stationary oil collector casing 71, hereinafter described. In accordance with the 20 above-described arrangement the transfer of oil or other fluid under pressure is effected between a non-rotating element (the oil transfer ring 59) and a rotating element (the head 21); leakage being prevented wholly by sealing contact between 25 the flat surfaces thereof. These flat surfaces are much easier to machine, to make oil tight and to maintain than circular surfaces such as are used in prior art arrangements, and in addition the arrangement described provides means whereby the oil seal surfaces may be readily adjusted 30 relatively to each other at assembly and in service without opening or disturbing the engine housing, thus providing means for quickly compensating for wear, should any occur. Obviously, such 35 adjustments may be made by moving the nut 58 along the threaded portion of the sleeve 57. The nut 58 is locked in place by a screw such as 72, Figs. 1 and 7. By means of slightly oversize 40 drilled holes such as 73 extending radially through the nut 58 and differently spaced tapped holes such as 74 in the sleeve 57 for the screw 72, the nut may be adjusted longitudinally of the sleeve portion 57 in extremely small increments. The 45 screw 72 has a hole 70 drilled through its shank close to its head, and when the screw is in place a locking wire is passed through the hole 70; the locking wire also being passed through a suitable circular groove 75 cut in the outer periphery of the nut 58.

In addition to the several advantages already 50 described that are possessed by the type of fluid transfer device included in this invention, there is the important feature of a completely balanced construction, whereby the pressure of the fluid has no influence nor effect tending to force the moving metal surfaces against the stationary contacting fluid-sealing surfaces. This is apparent from what has preceded, because, as explained, the grooves 62 and 67 in the stationary ring 59 each have the same area facing the two moving contact surfaces 61 and 58—a on the head 21 and nut 58 respectively. Consequently, when fluid under pressure enters the ring 59 through the tube 66, the total pressure exerted thereby against the surface 61 is equal and opposite to the total pressure exerted against the surface 58—a, and, therefore, the ring 59 is completely balanced longitudinally and the fluid-seal surfaces thereof are not forced against either of

the contacting surfaces 61 or 58—a by the action of the fluid.

The oil collector casing 71 is, in the manner hereinafter described, adapted to collect oil that may leak or be ejected from the hydraulic chamber or from the oil transfer ring 59. The casing 71 which is split, preferably in a horizontal plane, to facilitate installation, is secured to a plate 76 by bolts such as 77, and carries a packing ring 78 surrounding the cylinder portion 18 of the hydraulic chamber. The two halves of the casing 71 are bolted together by means of bolts 79, and the plate 76 is secured to the outer end, or nose 19, of the engine by any suitable means, such as studs or tap bolts, not shown.

The oil collector casing 71 surrounds the oil transfer ring 59 and keeps dust and dirt out of the associated elements. The casing 71 extends from the engine nose plate 76 to the round outer surface of the cylinder 18 and has a connection 82, Fig. 4, at the lower part thereof leading to the engine oil sump or other source of fluid supply. The upper half of the oil collector casing 71 may have an inside channel 83 to collect the oil thrown against the inside surface thereof and convey the same to the lower half of the casing. The oil pressure supply tube 66 extends through the oil collector casing 71 where the two halves join, and preferably has a gasket 84 surrounding the same as shown in Fig. 1 to form an oil seal and deaden vibrations.

The left hand end of the hydraulic cylinder 18 or the part thereof to the left of the piston 23 as shown in Fig. 1 is vented by means of a passageway in the form of a hole 86 which leads from this part of the chamber through the cylinder wall and head 21 to the chamber formed by the oil collector casing 71, the engine nose plate 76 and the head 21. Accordingly, any oil leaking past the piston 23 and any lubricant leaking past the rods 27 from the hub into the left hand end of the cylinder chamber will be thrown by centrifugal force into the passageway 86 and through it into the oil collector casing 71, whence it will be conveyed by gravity through the connection 82, Fig. 4, to the engine oil sump or other source of fluid supply which is ordinarily maintained at approximately atmospheric pressure.

Each blade socket 14 on the hub carries lubricant for lubricating the thrust bearings 46 and for the movable parts of the pitch changing mechanism located therein, such as the spur gear segment 34—a and the rack rod 33. If the lubricant is not equally distributed among all of the blade sockets, an objectionable unbalanced condition of the propeller may result, and some of the bearings and other parts may be insufficiently lubricated. Consequently, in accordance with another feature of the invention, means are provided whereby the total lubricant in all of the blade sockets is equally distributed through the action of centrifugal force acting thereon as the propeller rotates. For this purpose, in the left hand end face of the cylinder 18, as shown in Fig. 1, is formed a circular groove 87 which abuts on and is sealed by the flange 17 formed integrally with the hub 11 and sockets 14. A hole 88 is drilled through the wall of each socket 14 to meet the groove 87, and a slot 89 in the inner surface of the socket connects the hole 88 with the space 10 below the lowermost of the thrust bearings 46, thus providing a free passage from the interior of the socket to the groove 87. Accordingly, with such an arrangement centrifugal force acting on the lubricant in all of the blade sockets during 75

rotation of the propeller hub will force lubricant from any socket containing a greater amount of lubricant than the others along the slot 89 through the hole 88 into the circular groove 87 and thence, through similar passages, to the socket or sockets containing a lesser amount of lubricant. The flow of lubricant between sockets will thus continue until equalization of level in all sockets is obtained. Obviously, the groove 87 could be replaced by any other type of substantially circular conduit, such as tubing or pipe, adapted to connect the hole 88 in one socket with similar holes in the other sockets, or to connect the sockets individually with each other by means of relatively short conduits which may be either straight or curved.

The operation of the above described pitch changing mechanism is as follows:

Through driving connections, which will presently be reviewed, the mechanism as shown in Fig. 1 is so arranged that the pitch of the blades is caused to increase if the piston 23 is moved to the left, providing that the propeller is of the tractor type and that it rotates in a standard clockwise direction when viewed from the engine side thereof. It is apparent that the same effect could be obtained with a pusher type propeller, if the direction of rotation were reversed, or if each rack rod 27 were located on the opposite side of its mating gear 34—a from that shown in Fig. 1. When the piston 23 moves, it carries with it all of the rack rods 27, which are attached to it, and these rods must, therefore, move uniformly and at the same rate. As the rack of gear teeth 33 formed in each rod 27 is in driving engagement with the corresponding gear segment 34—a secured to each blade shank 38, it follows that all of the blades must rotate equally and at the same rate in response to any movement of the piston 23.

When the piston 23 is in its extreme right-hand position as shown in Fig. 1, the blades are so adjusted that their pitch is at the lowest limit required for ordinary service, and when the piston is moved to its extreme left-hand position the blade pitch is increased to the highest limit required for such service, which covers the range suitable for taking off, climbing and cruising at various speeds and altitudes. In the majority of cases, this range necessitates a variation in pitch angle of the blades amounting to about 20° to 30°, and the relative dimensions employed in the accompanying drawings are so chosen as to provide for a variation within such limits. Obviously, however, a greater or smaller variation may readily be obtained, as desired, by increasing or decreasing the stroke of the piston 23, or by decreasing or increasing the pitch diameter of the gear segments 34—a, or by any combination of such alterations.

As is well known in the art, when a propeller is rotating at operative speeds and the blade pitch is within the ordinary range, the action of centrifugal force on the blades is such as to tend to rotate each blade in its socket towards its low pitch limit, and this tendency, which is usually termed centrifugal twisting moment, attains considerable proportions, even in the case of relatively small propellers, amounting to at least several thousand inch-pounds of torque for a set of blades. In the present invention, the force thus developed is utilized, through the medium of the blade gears 34—a and rack rods 27, for moving the piston 23, Fig. 1, in a right-hand direction in the cylinder 18, so that no spring,

hydraulic pressure, or supplementary centrifugal device is required for this purpose under ordinary service conditions. However, it is apparent that such means may be readily incorporated in the arrangement herein described in cases where extreme pitch changes are required, as when provision is made for feathering the blades or reversing the pitch thereof.

As previously explained, oil or other fluid under pressure may be admitted to the cylinder 18 between the head 21 and the piston 23, Fig. 1, in order to move the latter to the left. It is apparent that the quantity of oil thus admitted to the cylinder will determine the extent of the longitudinal movement of the piston and, therefore, the degree of increase in the pitch of the blades. Conversely, it is equally apparent that the blade pitch may be decreased to any extent desired within the normal range by permitting oil in corresponding quantity to drain from the cylinder 18, thus allowing the piston 23 to be moved proportionately to the right by the force exerted thereon through the centrifugal twisting action of the blades.

The flow of oil or other fluid through the tube 66 and transfer ring 59 to and from the hydraulic cylinder 18 may be controlled by any of the well-known arrangements now in use. Such controls could be operated either manually or automatically as by a constant speed governor, or a combination of manual and automatic controls could be employed. The essential functions of the control would be to alter the pitch of the propeller blades by permitting fluid, such as oil, to flow through the tube 66 to and from the cylinder 18 in the proper amounts at the desired time. Another function of the control would be to maintain the propeller blades in fixed pitch positions by closing the tube 66 or an extension thereof, or by allowing fluid to flow therethrough to the cylinder in proper quantity to compensate for any leakage that may occur in the cylinder itself or in the conduits leading thereto.

From what has preceded, it is obvious that all of the objects enumerated herein are fully and successfully accomplished by the present invention, in the manner and through the means illustrated in the accompanying drawings and described in this specification. It is essential, however, to note that many alterations and modifications of design may readily be made in detail and general construction without in any way departing from the spirit and scope of the invention.

For example, by referring to Fig. 1, it is apparent that the cylinder 18 could be fabricated integral with the hub 11. It is also evident that the central barrel of the hub 11, which surrounds the propeller shaft 12, may be extended to the right in the general form of a tube, with the right-hand end thereof terminating approximately in line with the threaded end of the sleeve portion 57 of the cylinder head 21. The inside diameter of such an extension of the hub would be slightly greater than the outside diameter of the shaft 12 and its sectional area would preferably be as small as practical limitations would permit. The bores of the piston 23 and head 21 would be increased to fit slidably over the outer surface of this tubular extension, which would be made smooth, and dependent dimensions of these and other parts would be adjusted in accordance with such changes. The operation of a modified design of this nature would clearly be precisely the same as that of the arrangement

hereinbefore described, and it would have the advantage of being adaptable for use with established standard propeller shaft designs, which would require no special machining or other modification, but the cost of the hub would be increased appreciably.

As another example of an obvious modification, it is apparent that whereas in the above described arrangement, the piston 23 is movable longitudinally and the cylinder 18 is stationary with respect to the hub 11, this design could be readily reversed without any change in the principle of operation; that is, the piston could be fixedly secured to the shaft 12 or hub 11 and the cylinder could be detached from the hub and made slidable along the shaft. In such a case, the rack rods 27 would be secured by a suitable head or other means to the cylinder instead of to the piston, and each of these rods would also have to be re-located with respect to its mating blade gear, in addition to certain other minor alterations.

As a further example of a modification which may under certain circumstances be desirable,

25 a self-centering ringer or washer may be included in the oil transfer device to compensate for possible inaccuracies in the alignment of the component parts thereof. Such a washer would be installed between the nut 58 and the ring 59, Fig. 1, and its inside diameter would be slightly greater than the outside diameter of the sleeve portion 57 of the head 21 so as to permit of limited radial adjustment. The left-hand face of the washer would be ground flat to form an oil seal with the mating face of the ring 59 and its right-hand face would be substantially spherical in form, either convex or concave. The left-hand face of the nut 58 would also be spherical in shape and adapted to cooperate with the mating spherical face of the washer so as to substantially centralize the pressure exerted thereon by the nut when tightened, thus causing the oil-seal face of the washer to bear uniformly against the mating face of the ring 59, regardless of misalignment between the nut 58 and the sleeve 57. Preferably, the washer would be so mounted on the sleeve 57 as to be freely movable longitudinally thereof but restrained from rotation relatively thereto, as by means of a feather key or loosely fitting splines.

50 Among many additional obvious modifications are the following:

Whereas the fluid transfer ring 59 is shown as having circular ducts or grooves 62 and 67 in its opposite faces, it is apparent that the same principle of operation would still obtain if either or both of these grooves were omitted, providing that a corresponding groove or grooves were cut in the face 61 of the head 21 or in the face 58—a of the nut 58, or in both of the faces 61 and 58—a.

65 Whereas the design of the fluid transfer device above described provides a hydrostatically balanced ring between two adjacent fluid sealing members, it is apparent that in cases where such a balanced condition is not essential, the ring need have fluid sealing contact with only one adjacent member, and may have any suitable type of thrust bearing contact with the other adjacent member. For example, the ring 59 may have fluid sealing contact with the surface 61 of the head 21 and plain sliding contact against the thrust nut 58, in which case the groove 67 in the ring could be omitted and other means could be readily provided for lubricating the thrust surfaces.

Whereas the nut 58 is shown as having threaded engagement with the sleeve 57 of the head 21, it is apparent that as the function of this nut is primarily to press the ring 59 against the surface 81, the same result could be obtained by threading the nut to any other member, as the shaft 12 or a separate sleeve attached to the engine housing 81.

Whereas the sleeve 57 of the head 21 is shown as extending through the bore of the ring 59, it is apparent that the same function could be performed by a similar sleeve connected with the head 21 extending around the outer periphery of the ring 59 and having threaded engagement with the nut 58, providing that the conduit 66 and rod 69 were connected with the interior portion of the ring in any suitable manner.

While the invention has been described with reference to but a single preferred embodiment and certain modifications thereof, it will be apparent to those skilled in the art that various other and additional modifications of the invention may be made without departing from the spirit or essential attributes thereof, and it is desired, therefore, that only such limitations be placed thereon as are imposed by the prior art or are specifically set forth in the appended claims.

What is claimed as new and desired to be secured by Letters Patent is:

1. An aeronautical propeller adapted to be mounted on a shaft extending from a power plant, comprising a hub secured to the shaft having blades journaled therein for pitch change, each blade adjacent its butt end and within the hub having a gear thereon; reciprocable rack elements mounted within the hub each engaging one said blade butt gear, said rack elements having integral extensions passing slidably through the wall of said hub toward said power plant; an annular piston loosely fitted around the engine shaft between the hub and power plant and reciprocable therealong, to which the ends of said rack extensions are secured, said piston being supported by said extensions, whereby reciprocation of said piston simultaneously imparts pitch changing movement to said blades through said racks and gears; a cylinder secured to the face of said hub through which said rack extensions pass, said cylinder being concentric with said shaft and defining therewith an annular chamber in which said piston is movable, said piston having a loose fit relative to the wall of said cylinder, means to drain the hub end of said cylinder to the power plant, annular cup seal means on the face of said piston remote from the hub, said seal means engaging said shaft and the inner wall of said cylinder; a head secured to the end of said cylinder remote from the hub, said head embracing said shaft, means to seal said head to said shaft; said cylinder, piston and head rotating bodily with said shaft and hub; and relatively rotatable fluid transfer means wholly without the confines of said power plant having a part thereof formed in said head and an interengaging part thereof secured from rotation, for feeding pressurized fluid to the space bordered by said cylinder, said shaft, said head and said piston.

2. An aeronautical propeller comprising a shaft extending from a power plant, a hub secured to the shaft, said hub having blades journaled therein for pitch change, each blade adjacent its butt end and within the hub having a gear thereon; reciprocable rack elements

mounted within the hub each engaging one of said blade butt gears, said rack elements having integral extensions passing slidably through an inboard wall of said hub toward said power plant; an annular piston coaxially arranged around said engine shaft between the hub and power plant and reciprocable axially thereof, and secured to the ends of said rack extensions, whereby reciprocation of said piston simultaneously imparts pitch changing movement to said blades through said racks and gears; an annular cylinder for said piston, having an end face through which said rack extensions pass and one cylindrical wall rigid with said hub wall, guides in said hub for said rack elements whereby to support said piston from said extensions with a loose fit relative to the wall of said cylinder, said cylinder having a head rotatable with said cylindrical wall at the power plant end of said cylinder, annular seal means on said piston engaging the wall of said cylinder, fluid connection means feeding said cylinder at the cylinder head end of said piston, means for piloting said last named means coaxially with respect to said shaft and means for keying said fluid connection means against rotation with respect to the power plant while allowing radial movement of said connection means with respect to the power plant, and means providing a rotatable seal between said rotatable head and said keyed fluid connection means.

3. An aeronautical propeller adapted to be mounted on a shaft extending from a power plant, comprising a hub secured to the shaft having blades journaled therein for pitch change, each blade adjacent its butt end and within the hub having a gear thereon; reciprocable rack elements mounted within the hub each engaging one said blade butt gear, said rack elements having integral extensions passing slidably through the wall of said hub toward said power plant; an annular piston loosely fitted around the engine shaft between the hub and power plant and reciprocable therealong, to which the ends of said rack extensions are secured, whereby reciprocation of said piston simultaneously imparts pitch changing movement to said blades through said racks and gears; a cylinder secured to the face of said hub through which said rack extensions pass, said cylinder being concentric with said shaft and defining therewith an annular chamber in which said piston is movable, said piston having a loose fit relative to the wall of said cylinder, means to drain the hub end of said cylinder to the power plant, annular cup seal means on the face of said piston remote from the hub, said seal means engaging said shaft and the inner wall of said cylinder; a head secured to the end of said cylinder remote from hub, said head embracing said shaft, means to seal said head to said shaft; said cylinder, piston and head rotating bodily with said shaft and hub; and relatively rotatable fluid transfer means wholly without the confines of said power plant, said fluid transfer means comprising a parallel sided annular groove in a portion of said head, said head having an opening establishing communication between the cylinder space and one of the parallel sides of said groove; a parallel sided ring fitted within said groove, means to secure said ring from rotation, and a pressure fluid conduit attached to said ring, the latter having passages formed therein to conduct pressure fluid to both side faces thereof from said conduit, and annu-

13

larly around said ring; and means to adjust the clearance of said ring in said groove.

HOWARD MURPHY.
ROBERT E. LINSE.
